(57) **CLAIM**

The ornamental design for the mobile shelf sidewall, as shown and described.

DESCRIPTION

FIG. 1 is a perspective view of a mobile shelf sidewall according to an embodiment of our design.

FIG. 2 is a first side view thereof.

FIG. 3 is a second side view thereof.

FIG. 4 is a top view thereof.

FIG. 5 is a bottom view thereof.

FIG. 6 is a first edge view thereof; and,

FIG. 7 is a second edge view thereof.

The broken lines shown in the drawings are for the purpose of illustrating portions of the mobile shelf, which form no part of the claimed design.
